UNITED STATES PATENT OFFICE

GEORG ZAPF, OF COLOGNE, GERMANY, ASSIGNOR TO FELTEN & GUILLEAUME CARLSWERK ACTIEN-GESELLSCHAFT, OF COLOGNE-MULHEIM, GERMANY

PRESSURE-PROTECTING COVERING FOR SUBMARINE CABLES

Application filed October 23, 1929, Serial No. 401,911, and in Germany December 1, 1928.

This invention relates to a cable for great sea depths and the object of the invention is to improve the mechanical properties of the pressure-protecting coverings hitherto proposed for such cables in order to render them capable of use also for the greatest depths of sea. In some forms of construction the means used for increasing the compressive strength also improved the electric properties of the cable.

A hollow conductor in the form of a tube of profile wires may be rendered more resistant to high pressures by the insertion of a twisted strip or of a supporting core of cross-shaped cross-section. As compared with a reinforcement of the profile wires for obtaining the same effect, this arrangement has the advantage that the cable provided with the pressure-protecting covering still possesses a sufficient flexibility.

The invention consists in a pressure-protecting tube having an inner supporting member consisting of a number of separate flat or profile bands which abut against one another radially in the axis of the cable and are stranded together with the profile wires of the pressure-protecting tube. A characteristic of this construction is its increased compressive strength and stability of form.

The accompanying drawing illustrates in cross-section a form of construction in which the supporting walls consist of bands the width of which is equal to half the outer diameter of the pressure-protecting covering and which are stranded together with the pressure-protecting covering. *a* are the supporting walls, *b* and *c* is a two-layer pressure-protecting covering, *d* is the lead sheathing and *e* the armouring.

This form of construction has the advantage, that in addition to increasing the compressive strength, the supporting walls can be used at the same time as means for screening the conductors of the groups of conductors of the cable electrostatically with respect to one another. In this way the use of separate screening means is dispensed with.

What I claim is:

1. A pressure-protecting covering for deep sea cables constituted by profile wires and

having an inner supporting member for increasing its compressive strength the said supporting member consisting of profile bands inserted at regular distances between the profile wires of the pressure-protecting covering and stranded together with the said profile wires.

2. A pressure-protecting covering for deep sea cables as claimed in claim 1 and in which the supporting member serves at the same time for statically screening the conductors of the cable.

In testimony whereof, I have signed my name to this specification.
